(57) CLAIM

The ornamental design for a golf tee, as shown and described above.

DESCRIPTION

FIG. 1 is a perspective view of a tee embodying my invention;

FIG. 2 is an enlarged scale front elevational view thereof;

FIG. 3 is an elevational view rotated 60° from FIG. 2;

FIG. 4 is a right side elevational view of FIG. 2;

FIG. 5 is a top plan view thereof; and,

FIG. 6 is a bottom plan view thereof.
